BEDSPRING

Solomon Raduns, Brooklyn, N. Y., assignor to
Greenpoint Metallic Bed Company, Inc., Brooklyn, N. Y.

Application May 13, 1937, Serial No. 142,337

1 Claim. (Cl. 5—269)

The present invention relates to bedspring constructions.

In the usual type of bedsprings, such as for example shown in my copending application Serial No. 88,921 filed July 6, 1936, and in Patent 1,964,296 granted to Greenpoint Metallic Co., Inc., on the application of Louis C. Moeckel, bed spring constructions were disclosed in which face of the spring construction is provided with longitudinal strips of metal connected by springs or in other manners to the vertically disposed coil springs positioned between the upper and lower frames of the bedspring.

It has now been found desirable for said purpose to make these strips more flexible and it among the objects of the present invention to provide an improved strip construction and bedspring construction including such strips in which the strips will be quite flexible or relatively soft.

It is a further object of the present invention to provide an improved bedspring construction in which the springs will be better balanced and other objects will be obvious or will appear during the course of the following specification.

In accomplishing the above objects according to one embodiment of the present invention the strips of the spring are formed of interlinking coil wires or of flexible wires, cables, or ropes which ropes or wires are preferably connected to plates or to small horizontal extending springs, which in turn are connected to the vertical coil springs extending between the upper and lower frames of the bedspring.

It is desirable that these flexible strips be held laterally extended so that they will be expanded and not collapse when displayed or when the weight of a body is not resting thereon.

At the same time when a body is resting thereon the strip should have sufficient flexibility as to permit greater conformation to the shape of the body and enhance flexibility at the upper face of the spring.

In the drawings which illustrate one of the several embodiments of the present invention to which, however, the invention is by no means restricted.

Fig. 1 is a fragmentary face view of one type of spring according to the present invention.

Fig. 2 is the fragmentary face view of another type of spring according to the present invention.

Fig. 3 is a fragmentary cross sectional view upon a large scale upon the line 3—3 of Fig. 2.

Fig. 4 is a face view upon an enlarged scale of

one end of one of the flexible strips of Figs. 1 and 2, a portion of the end clip being broken away.

Fig. 5 is a transverse section upon the line 5—5 of Fig. 4 showing the clip for holding the end of the flexible band or strip.

Fig. 6 is a perspective view of the each clip of Figs. 4 and 5 before attachment to the strip.

Fig. 7 is a plan view of the end of an alternative form of flexible strip.

Fig. 8 is a cross section upon the line 8—8 of Fig. 7.

Fig. 9 is a fragmentary plan view of an alternative spring construction including the flexible band of Figs. 4 and 5.

Referring to Figs. 1 and 2, the spring construction is provided with a frame 10 in Fig. 1 and 10' Fig. 2 (similarly functioning parts in Fig. 2 being indicated by the same numerals as in Fig. 1 but primed).

The vertical coil springs 11 and 11' extend between the upper frame 10 and the lower frame (not shown) and they are connected by their uppermost coils to the upper frame at the points 25 12 by suitable riveted or other connections.

Extending longitudinally of the spring are the flexible strips 13, to the construction of which the present invention is most particularly directed.

30 These flexible strips 13 may be composed as best shown in Figs. 3 and 4 of spiral or helical pieces of wire 14', which are interlinked, as indicated at 15 in Fig. 4, and which embrace the side wires 16 of the band.

35 The ends 17 of the wires 16 and the ends 18 of the spirals 15 are gripped in the clip or end holder 19, which has two side plates 20, bent at 21 and provided with the intermeshing teeth 22.

The sides of the lower plate 20 are inturned as indicated at 23 to cover the sides of the closed clip. When the plates 20—20 are closed as indicated in Fig. 5, they will firmly grip the ends 17 and 18 of the wires 16 and the coils 14.

The openings 24 enable convenient attachment of connecting springs 25 and 26, as indicated in Fig. 1, which connecting springs at their other ends are engaged at 27 with the uppermost turns of the coil springs 11.

In the recesses indicated at 28 in Fig. 4 may be connected the ends of other coil springs 29, as shown in Fig. 1, which at their other ends 30 are connected to the uppermost turns of the coil springs 11.

The horizontal springs 25, 26 and 29 serve to hold flexible strips 13 laterally extended, pre-

venting them from collapsing, at the same time they permit them to have sufficient flexibility to more readily conform to the shape of a body resting thereon.

At the same time the mesh effect of the strips 13 as shown in Figs. 1, 2 and 4 gives a better eye effect to the spring and greatly improves the balance and flexibility of the spring construction.

The strips as shown at 13 in Figs. 1, 3 and 4 are inexpensive to construct and are readily assembled with little expense and with as much ease as flat metal strips.

If desired, plates such as indicated at 31 and 32 in Fig. 2 may be employed at spaced intervals to carry the connected springs 25', 26' and 29' and also to maintain the flexible strips 13' in laterally extended position.

As shown best in Fig. 3, the plate has upturned fingers 33 which embrace the side wires 16' of the flexible band 13', said fingers holding the wires 16' apart.

The corners of the plates may be provided with holes as indicated at 34 Fig. 2 to receive said coil springs 29'.

If desired, the plates 31 may be extended as indicated at 35 to embrace the end of the strip 13' and to constitute end clipping devices, such as shown in Figs. 4 to 6. The ends of the strips 13 and 13' may also be embedded in a lead or other die casting.

In Figs. 7 and 8 (similarly functioning parts as in Figs. 1 to 6 being indicated by the same numerals with a superior 2) the end structure 26² is provided with the usual openings 24² and it grips the cables 15² which may be composed of a large number of wires twisted together.

These cables 15² preferably clipped together at spaced intervals by the clips 32² constitute a flexible band member. Diagonal springs similar to springs 25, 26 and 29 may be connected to these bands in the manner shown in Figs. 1 and 2.

Of course instead of the cables 15², it is also possible to use wires or other flexible members.

In the structure shown in Fig. 9, the plates 32³ are provided with ears 33³ of similar function to

the plates 31 and 32 of Figs. 2 and 3 (similar functioning parts being indicated by the same numerals provided with a superior 3).

The flexible bands 13³ are connected to laterally extending coil springs 35 in addition to the diagonal coil springs 29³, the construction as shown in Fig. 9 giving a spring face of high artistic value and of particularly satisfactory balanced character.

Many other changes could be effected in the particular features of bedsprings disclosed and in specific details thereof, without substantially departing from the invention intended to be defined in the claim, the specific description herein merely serving to illustrate certain elements by which, in one embodiment, the spirit of the invention may be effectuated.

What is claimed is:

A bedspring construction of the type having an upper rectangular frame and a plurality of main coil springs, having vertical axes arranged in lateral and longitudinal rows and supporting said upper frame, the upper rungs of the peripheral coil springs being directly connected to the upper frame, a plurality of bands of woven wire mesh extending longitudinally between and substantially spaced from the longitudinal rows of said main coil springs, each of said bands being composed of a plurality of interlaced spiral wires extending side by side, with straight edge wires extending through the outside spiral wires, clips at the ends of said bands holding together and grasping the ends of said spiral and straight wires, laterally extending plates carried by said bands, said plates having struck down ears engaging said edge wires to hold said bands laterally extended, said plates being arranged on said bands between the lateral rows of coil springs, the extensions of said plates laterally beyond said rows being provided with openings and short horizontally disposed diagonally extending coil springs connected in said openings and at their other ends being connected to the top rungs of said main coil springs.

SOLOMON RADUNS.
